WAIST RESTRAINER

Raleigh McCabe, Chicago, Ill.

Application August 19, 1938, Serial No. 225,661

5 Claims. (Cl. 2—41)

This invention relates to a waist restrainer, abdominal support and reducing band in the form of a girdle adapted to be placed around the waist to be used as a reducing garment and to maintain the shape of the abdomen while permitting free and unrestricted movements of the body and legs.

It is an object of the invention to provide a novel and simple construction for a device of the above character by which pressure may be applied to tighten the device entirely around the waistline so as to draw in the abdomen particularly at the diaphragm or stomach without being oppressive and without pressing on the spine, the device permitting a wide range of adjustment and maintaining its shape, as well as being light in weight and economical to manufacture.

Another object of the invention is to provide a waist restrainer or reducing band of the character set forth which may be made in a step-in style and which will give a maximum of comfort in use.

Other objects and advantages will appear and be brought out more fully in the following specification and drawing, wherein:

Fig. 1 is a sectional plan view of the device;

Fig. 2 is a front elevation partly broken away to show the anchoring of the laces; and

Fig. 3 is a rear elevation.

Referring more particularly to the drawing, the waist restrainer or abdominal support is shown as comprising a main front section 10 made up of light open mesh inelastic textile fabric or cloth with open interstices adapted to embrace the abdomen at the front and sides. This portion 10 is of substantially oval or lenticular form at the front, the top and bottom edges being convex in opposite directions as indicated at 11 and merging into tapered ends 12, the opposite edges of which are oppositely concave, so that the top and bottom edges from the center point to the ends are first convex and then concave, thus forming a substantially ogee or reverse curve. These edges are provided with bindings or other finished edge portions 13. Inserts 14 consisting of short lengths of stretchable elastic material or short sections thereof, are attached to the ends of the portions 12 as indicated at 15 by stitching or otherwise so as to leave flat joints 16 for disposition against the body and the opposite vertical edges of the elastic sections 14 are sewed or otherwise connected as shown at 16 to an inelastic cloth section 17 preferably of canvas or the like disposed centrally at the back. Upon this central back section are mounted a

pair of stays or bones 18 which are spaced apart at the center as indicated at 19 and contained within pockets 20 formed as part of the section 17 or mounted thereon by stitching or otherwise as shown. Interposed between the pockets and the section 17 is a strip 21 with loops 22 at the ends beyond the pockets 20 to take elongated metallic loops or the like 23 which are in turn engaged by the rebent portions 24 of the inelastic strip or band 25 of canvas tape or the like which is much narrower than the portions 10 and 12 of the garment.

It will be noticed that the back canvas section with the two vertical or parallel stays or bones are thus in the form of hinged sections, the same being flexible between the stays so as to straddle the spinal column to brace the back at each side of the spine without pressing directly on the latter, and by having the top and bottom edges of the band cut on reverse curves convex from the front to the sides and concave from the sides to the rear or back adjacent each side of the spinal column, proper conformity to the waistline of the body is insured without interfering with the movements of the body in bending in any direction or free movements of the legs. At the front, the portion 10 is provided directly in the center with a vertical canvas or like heavy strip made into a pocket 26 in which is disposed an enclosed central vertical stay 27 which, together with the stays 18 serve to retain the belt or band distended and flat. The pocket 26 or strip of inelastic fabric forming the same is stitched at the upper and lower ends along with the marginal edges of the part 10, as with the binding 13 and the opposite vertical edges of the strip or pocket 26 are left free from the lines of stitching 28 to the vertical edges, thereby forming flaps in which are disposed a plurality of vertically spaced rows of eyelets or the like 29. These eyelets receive laces 30 which are crossed over in front as indicated at 31 and extend between the eyelets at the back or inside as indicated at 32, at which point the laces are anchored by the rows of stitching 28 or otherwise so as to keep the laces from shifting lengthwise. These laces which are of inelastic material or in the form of tapes, are then extended in opposite directions at their extremities and in convergent relation as indicated at 33, these convergent portions being anchored at their outer ends as indicated at 34 to one end at the under portions of the band 25 forming a draw strap, band or belt outside of the sections 10, 12 and 14 after being passed through the loops 23 and rebent as shown at 24 or folded on them-

selves. The outer portions of the band or belt 25 are also extended forwardly over the elastic inserts or sections 14 and the sections 12 and 10 around the sides and front of the device where 5 one end is fastened as indicated at 35 to a buckle 36. The free end of the other side of the band or belt is engaged with the buckle 36 and constitutes an extensible portion 37 by which the device may be tightened centrally around the 10 waist and abdomen from the opposite edges of the central back section 17 so as to act practically entirely around the body. In order to cause the front section 10 to more properly conform to the abdomen and assist in the reducing 15 action, a pair of upwardly divergent pockets 38 are secured upon opposite sides of the central front pocket 26 and converge downwardly from points in spaced relation to the pocket 26 at the top edge to the edges of the pocket at the bottom edge of the section 10 as particularly shown 20 in Fig. 2 of the drawing. These pockets are stitched to the inelastic cloth section 10 and also to the top edges thereof, the stitchings 39 forming pockets for receiving stays or bones 40 which, 25 like the other stays, are made of flexible or resilient metal or other strips so as to flex and conform to the body for proper fit, as well as during movements of the body in bending in any direction. The particular location of these stays 30 is of special benefit in maintaining a graceful form to the body and in confining the abdomen as a part of the restraining, supporting and reducing functions.

In the use of the device, the band or belt 25 is loosened at the buckle 36 and applied as a step-in being slipped upwardly over the legs and hips and adjusted to the body at and above the hips at the abdomen and waistline, stomach or diaphragm to be restrained, held in or contracted and 40 supported while permitting free and unrestricted movements of the body in bending at the waist or otherwise, especially due to the flexible character of the construction and permitting free movements of the legs. A wide range of adjustment is 45 permitted by reason of the sections of the belt or band 25 being extended through the loops at the back and folded upon themselves so as to effectively draw the device into a confined area at the anchored front portion and between the same and the loops at the back due to the overlapping and 50 divergent lace portions of the belt or band permitted by the buckle 36 or other suitable adjustable connection for the free ends of the belt. Owing to the fact that the laces are anchored 55 intermediately of the ends thereof in back of the pocket 26, shifting of the laces is prevented so that the latter will always lie flat against the section 10 and assist the stays 27 and 40 in maintaining the section 10 flat and snugly conforming 60 to the body at the front, especially on account of the convergent relation of the laces from the pocket 26 to the end portions 34 of the band or belt 25 to which the extremities of the laces are anchored as previously described.

65 While I have illustrated and described the preferred form of construction for carrying my invention into effect, these are capable of variation and modification without departing from the spirit of the invention. I, therefore, do not wish 70 to be limited to the precise details of construction set forth, but desire to avail myself of such variations and modifications as come within the scope of the appended claims.

75 Having thus described my invention, what I

claim as new and desire to secure by Letters Patent is:

1. A waist restrainer comprising an inelastic body section with tapered ends extending around the sides and toward the back of the wearer, a 5 back section of inelastic material having a vertical stiffening member, elastic inserts between said back member and the ends of the body section, stiffening members at the front of the body section and a body restraining member connected to the back section and having overlapping portions consisting of inner and outer sections, the inner section being anchored at the front and the extremities of the other sections being adjustably connected at the front. 10

15 2. A waist restrainer comprising an inelastic fabric body section having oppositely convex top and bottom edges tapering toward their extremities and terminating in oppositely concave edge portions cut on reverse curves, an inelastic section 20 at the back having spaced vertical stays, elastic inserts in said body section and between the same and the back section, the back section being pliable between the stays and having loops at each side, an inelastic band extended through 25 the loops and folded on itself with two end portions extending forwardly around the outside of the body section, a vertical pocket centrally at the front having a stay member and spaced eyelets on each side thereof, laces extended 30 through said eyelets and anchored at the back of the pocket and stay member, the end portions of said laces being extended to the inner ends of the band and anchored thereto, the overlying portions of the band being adjustably connected 35 at the ends thereof.

40 3. A waist restrainer comprising an inelastic fabric body section having oppositely convex top and bottom edges tapering toward their extremities and terminating in oppositely concave edge portions cut on reverse curves, an inelastic section 45 at the back having spaced vertical stays, elastic inserts in said body section and between the same and the back section, the back section being pliable between the stays and having loops at each side, an inelastic band extended through 50 the loops and folded on itself with two end portions extending forwardly around the outside of the body section, a vertical pocket centrally at the front having a stay member and spaced eyelets on each side thereof, laces extended 55 through said eyelets and anchored at the back of the pocket and stay member, the end portions of said laces being extended to the inner ends of the band and anchored thereto, the overlying portions of the band being adjustably connected 60 at the ends thereof, and oppositely inclined and downwardly converging pockets with stay members upon opposite sides of the vertical pocket and stay member at the front of the body section. 65

70 4. A waist restrainer comprising an inelastic fabric body section having oppositely convex top and bottom edges tapering toward their extremities and terminating in oppositely concave edge portions cut on reverse curves, an inelastic section 75 at the back having spaced vertical stays, elastic inserts in said body section and between the same and the back section, the back section being pliable between the stays and having loops at each side, an inelastic band extended through the loops and folded on itself with two end portions extending forwardly around the outside of the body section, and an adjustable buckle con- 80

nection between the overlying end portions of the band at the front.

5. A waist restrainer including a body encircling portion having an adjustable belt comprising laces anchored at the front and sections connected to the laces, said sections being folded

upon themselves and anchored to the outer ends of the laces and slidably supported at the back of the body encircling portion, certain ends of said sections being adjustably connected at the front.
